UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAGGING-MACHINE.

1,137,376.

Specification of Letters Patent.

Patented Apr. 27, 1915.

Application filed September 6, 1910. Serial No. 580,716.

To all whom it may concern:

Be it known that I, ADELMER M. BATES, a citizen of the United States, residing at Chicago, in the county of Cook and State 5 of Illinois, have invented a certain new and useful Improvement in Bagging-Machines, of which the following is a specification.

My invention relates to improvements in bagging machines, and has for its object to 10 provide an improved apparatus for filling valve bags, and is based upon subject matter divided out of my co-pending application for bagging machines, No. 560,533, filed May 10, 1910.

15 It is illustrated in one form in the accompanying drawings, wherein—

Figure 1 is a front elevation of a portion of the machine; Fig. 2, a section along the line 2—2 of Fig. 1; Fig. 3, a detail section 20 showing a modification; Fig. 4 is an elevation showing a detail of Fig. 3.

Like parts are indicated by like letters in all the figures.

The end frames A carry at their tops the 25 parallel spaced channel irons A¹ which form the backbone of the filling machine and at the same time form the two side walls of the feeding pocket A², which pocket is in communication at its top with the feeding 30 throat A³ in communication with the supply hopper A⁴ and controlled by the rotary feeder A⁵ mounted upon the shaft A⁶, and at its bottom with the propeller pocket A⁷ containing the rotary propeller A⁸ mounted 35 upon the shaft A⁹ in opposition to the filling throat A¹⁰ and filling tube A¹¹. It will be observed that the propeller pocket is in fact and effect a part of or a continuation of the feeding pocket, although for purposes 40 of convenience in describing the drawing I have given it a separate letter. The shaft A⁹ carries the driving pulley B and is provided with the pinion B¹ in mesh with the gear B² which carries the pulley B³ and is 45 rotatably mounted on the stud B¹². The pulley B³ carries the belt B⁴ to drive the pulley B⁵ upon the shaft A⁶. The idler pulley B⁷ mounted upon the bell-crank lever B⁸ is in engagement with the belt B⁴ 50 and held thereagainst by means of the weight B⁹ which may be lifted to relieve the tension in the belt by means of the cord B¹⁰ controlled by the handle B¹¹. The filling tube A¹¹ is mounted upon the A-frame 55 C which is supported at its bottom by any

suitable means not shown, and carries at its top the adjustable link C¹ pivotally mounted upon one of the channel bars A¹ and which is adapted to regulate the position of the tube A¹¹, longitudinally with respect to the throat A¹⁰.

The modification illustrated in Fig. 3 shows the channel bars A¹ as dispensed with, and shows the relative position of the feeding throat and supply bin reversed with relation to the rest of the machine and shows the feeding throat frame D carried clear across the machine and supported upon the end pieces, thus taking the place of the channel bars A¹ as the back bone of the machine. The feeding throat and propeller pocket are now in closer relation one to the other, there being no intermediate pocket between them, and the link C¹ is now pivoted upon a portion of the hopper B rather than upon one of the channel bars A¹.

The use and operation of my invention are as follows:—I provide a propeller pocket in which rotates a propeller and from which leads the feeding throat but in order that the flow of material through the feeding throat may be constant, I provide means for maintaining the pressure upon the material in the propeller pocket at a constant point. This I do by interposing in the connection between the supply hopper and the feeding pocket a rotary multiple pocket feeding device which rotates responsive to the rotation of the propeller and the rotation of which may be stopped at the will of the operator to cut off the supply. This device not only maintains the pressure of the material upon the propeller at a constant point but it materially reduces the pressure. This is desirable because the materials, such as cement, which are run through this machine and are kept in the storage or delivery bins exerts pressure much as does a column of water. Since the propeller travels at a very high speed it is desirable that this pressure be kept as low as possible in order to prevent heating of the material and the propeller. This the feeder does since it separates the bottom of the bin from the propeller pocket, thus making the effective height of the column of material equal to the distance between such feeder and the propeller. The feeder takes the form of a number of pockets in the periphery of a roll or cylinder, which rotates between curved walls. As it rotates

the pockets are filled when in the supply bin and emptied when they reach the supply hopper. The feeder is driven from the same shaft that carries the rotary propeller and bears a fixed relation in its speed to the speed of the rotary propeller and may be disconnected from such shaft, whereupon the supply of material to the propeller will be interrupted and the propeller will revolve 6 freely in its pocket, without being in contact with any of the material to be fed.

It will be evident that I have shown in my drawings an operative device, still many changes might be made in size, shape and 15 arrangement of parts without departing materially from the spirit of my invention, and I wish, therefore, that my drawings be regarded as in a sense diagrammatic.

It will be observed, therefore, that in my 20 device the material flows downwardly under the force of gravity into the feeding pocket, being controlled in its flow thereto by the feed regulating cylinder, which cylinder is operated in unison with the propeller which 25 is completely inclosed in the bottom of the feeding pocket. Thus the flow of material to the feeding pocket bears a direct and constant relation to the rapidity with which the material is discharged by the propeller 30 therefrom.

Since my device is primarily designed to be used in connection with valveless bags, which are ordinarily filled from one corner and supported from the filling tube, I have 35 provided a horizontally disposed filling tube

tangential to the propeller, and as the material passes through the machine it first falls under the influence of gravity in a substantially vertical line to the propeller, by which it is violently projected in a horizontal direction out through the filling tube into the bag. 40

I claim:—

1. A bag filling machine comprising a supply bin, a mechanical feeding device at the bottom thereof, a feed hopper into which said feeding device discharges, a propeller located at the bottom of said hopper and a discharge tube leading therefrom, means for actuating said propeller and said feeding device in unison, and means for discontinuing the operation of said feeding device and said propeller, without interfering with the operation of the propeller. 45

2. A bag filling machine comprising a supply bin, a mechanical feed control device at the bottom and discharging from said bin, a small charge retaining hopper located beneath and fed by said feed control device, a propeller located at the bottom of said hopper, a discharge tube in line with and fed from said propeller, said propeller and said feeding device being normally driven in unison and means for disconnecting said feeding device and said propeller without interfering with the operation of the propeller. 50
